STERN CONSTRUCTION FOR MOTOR BOATS AND THE LIKE

Filed Dec. 10, 1929

UNITED STATES PATENT OFFICE

JONATHAN COOK SMALL, OF PROVINCETOWN, MASSACHUSETTS

STERN CONSTRUCTION FOR MOTOR BOATS AND THE LIKE

Application filed December 10, 1929. Serial No. 413,020.

This invention relates to improvements in marine propulsion and particularly to the increasing of the speed of motor driven boats which have heretofore been retarded by inadequate relations between hull design at the stern and the propeller power.

There have been many and radical developments in motor boat design particularly along the type of the so-called speed boat, but in the more sturdy types of craft the lighter powered motors have not been productive of increases in speed such as seemed reasonably to be expected by the horse power made available.

15 To illustrate the principles of my invention, I call attention to a type of craft in general use and well illustrating the problem. These boats may be readily distinguished from the speed boat type in that they 20 are of generally deeper draft and generally of the squarer stern type.

These are usually, but not necessarily of the duty type of motor boat in which certain roominess is required and sea worthiness an 25 absolute prerequisite.

Such boats represent the substantial interests of deep water business such as that of the fisherman. For such, sea worthiness is most important.

30 By way of illustration I cite the usual proper coast boat adapted for off shore work as for example the very practical conditions under which the fisherman must operate. The modern market for the catch, the difficulties of getting available bait, the demands 35 of any and all season supply impose conditions which call for sea worthy, capable craft, but of speed heretofore unknown.

The requirements for such a boat are most 40 exacting and they are difficult to design. So far, the practical ideal boat for such work has not been produced. I therefore base my disclosure on my own experience in redesigning or readapting standard types to a 45 uniform improvement in performance.

I may take as an illustrative problem that of the square stern, rather deep draft, keel type of the coast fisherman. Such boats have 50 usually been provided with powerful engines but even with ample engine power

soon reach a limit beyond which they can not be driven though below that of theoretical engine capacity.

The problem was to provide for increased speed without sacrificing the desired feature 55 of design.

The operation of such a square stern boat is greatly affected by the suction at the stern caused by the passage of the boat through the water, resulting in a dragging of a volume of 60 water of great weight. It has been observed that this suction increases so as to reach its maximum when the boat is moving at 12 knots an hour and when it is so great that with the ordinary equipment of a fishing vessel, 65 it is practically impossible to exceed a speed of 12 knots. The drag increases very rapidly as the speed is increased from ten miles to twelve.

In the operation of any propeller in the 70 water, there is failure to realize the theoretical or full value or power of the screw action by reason of the fact that the water not being solid tends to slip away from the propeller blades; this slipping of the water is, of course, 75 greatest toward the surface of the water as the surface of the water indicates the way of least resistance.

My invention contemplates by addition or 80 by original building, the presence of stern factors which prevent the stern settling under the submersion tendency of the propeller and the back drag on the stern itself—also the slippage of the propeller thrust.

In general, I provide on each side of the 85 stern what, as shown, is a box like compartment structure in the nature of a counter sponson and at a slight angle to the race of the propeller.

The difficulties seemed to be that these boats at certain speeds peculiar to their design developed a stern drag that so rapidly diminished the otherwise possible acceleration as to make a practical speed limit regardless of reserve engine power. In addition and under such conditions, the propeller resistance diminished so that added propeller speed seemed to be of no avail.

While my invention is capable of embodiment in original structures my immediate 100

practical problem was that of discovering the deficiencies of craft already built and in service and variously engined.

In fact the problem is generally one of 5 actual as against theoretical performance. An internal combustion engine seems to vary in performance in boats of different design and different engines seem to give different results in different designs of boat.

10 For example, I found motor boats of good design and well motored and otherwise generally satisfactory, whose speed limit seems to be fifteen knots no matter how hard driven.

15 When equipped according to my invention in the very simple and inexpensive form shown the same boat otherwise unchanged did twenty-two and one-half knots. The practical difference in the service use of this 20 boat made one day's work out of what had been one and one-half or two days.

In such practice and by applying the principles of my invention on the basis of removable auxiliary stern lifting members of 25 sponson like character, it is possible by test to make adjustment to make up for the stern sag differential between the stern design and the propeller power.

When so adjusted and fitted these members 30 operate as follows:

In starting the stern usually settles somewhat slightly submerging the auxiliary chambers. The settling is, however, soon overcome and as the boat picks up speed the stern 35 rises to normal water line. This relieves the stern of any back drag and the wake runs clean. Furthermore, the downward pitch of the box bottoms takes slightly of the propeller race thrust which not only keeps the 40 stern sustained, but steadies the propeller race.

In practice my invention may find many 45 embodiments. To make simple the disclosure I show but one and that a case of such ordinary occurrence that it involves the general solution for an immediate demand.

The drawings therefore show an average 50 type square stern motor boat of what might be called a general utility type. It is to be understood as of suitable power engine equipment.

In the drawings:

Fig. 1 is a side view of a stern equipped 55 in accordance with my invention.

Fig. 2 a stern view thereof, and

Fig. 3 a bottom view.

Considering the problem of such a boat as is indicated there is the general hull portion 1 framed on a general keel member 2 and having a stern 3 and counter 9.

The details of design are not involved in the application of principle.

As shown, the stern has an overhang and the propeller 4 is on a shaft 5 which has a slight downward pitch.

With such a design I equip with a pair of lateral box cells, sponson members. These consist of longitudinal side members 6 and 7 fitted at their upper edges to conform to the contour of the counter and straddling 70 the rudder post.

These side members 6 and 7 are fitted with a bottom 8 the forward edge of which is fitted to the hull at its line of contact.

The rear of each chamber is closed by an 75 end piece 9.

Where the stern design is such as to permit this to overlap the stern it may be made to constitute a supporting member.

The ends 9 are scuppered as at 10 in order 80 to accommodate any leakage.

The bottom members 8 are given a slight downward pitch so as to receive the race of the propeller 4. This steadies the thrust of the propeller and imparts to the stern a 85 slight upward resultant.

Furthermore, when such a boat as above suggested is propelled at a speed exceeding about twelve miles an hour each compartment relieves itself of all water that may be in it, thus creating a greater buoyancy 90 under the stern of the boat.

When this condition or situation has been brought about the bottom of the compartment is still below the level of the water which is alongside the boat, being kept from rushing in from the sides by the projecting sides of the compartment. It is also kept from coming in at the open end of the structure by the depression in the wake caused by the drag of the stern. The effect of this in greatly increasing the speed of the boat seems to result in further reducing the slippage, by reason of the decrease of friction due to the reduction of the displacement and the resulting lightening of the load on the engine.

What I therefore claim and desire to secure by Letters Patent is:

1. In combination with the stern of a motor driven boat, of a pair of stern sponson boxes disposed one on each side of the rudder post and having a flat bottom pitched slightly downwardly and rearwardly and disposed above the propeller race.

2. In combination with the stern of a motor driven boat, of a pair of stern sponson boxes disposed one on each side of the rudder post and having a flat bottom pitched slightly downwardly and rearwardly and disposed above the propeller race, and of displacement substantially equal to the stern submersion tendency of the boat at maximum propeller speeds.

3. In combination with the stern of a motor boat, a pair of attached flat bottomed sponsons disposed one on each side of the rudder post and having their bottom at substantially normal water line and slightly downwardly and rearwardly inclined into the propeller race.

4. In combination with the stern of a motor driven boat, a pair of stern chambers disposed one on each side of the rudder post and having a flat bottom pitched slightly downwardly and rearwardly and disposed above the propeller race and of displacement substantially equal to the stern submersion tendency of the boat at maximum propeller speeds.
5. In combination with the stern of a motor boat, a pair of flat bottom counter boxes disposed one on each side of the rudder post and having their bottoms at substantially normal water line and scuppered at their rear ends.
- 10 6. In combination with the stern of a motor driven boat, a pair of boxes each consisting of sides bottom and end members, the sides and bottom fitted to the counter, one on each side of the rudder post, the box ends overlapping the stern and supported thereby.
- 15 7. In combination with the stern of a motor boat, a pair of auxiliary chamber members disposed one under each counter and having a combined displacement substantially counteractive of the submersion tendency of the propeller at maximum speed.

In testimony whereof I affix my signature.
